UNITED STATES PATENT OFFICE.

RICHARD C. BIGHAM, OF SPOKANE, WASHINGTON,

REPAIR-BOOT.

1,303,154.

Specification of Letters Patent.

Patented May 6, 1919.

Application filed January 11, 1919. Serial No. 270,676.

To all whom it may concern:

Be it known that I, RICHARD C. BIGHAM, a citizen of the United States, residing at Spokane, in the county of Spokane and State of Washington, have invented new and useful Improvements in Repair-Boots, of which the following is a specification.

This invention relates to improvements in repair boots adapted to be inserted between the inner tube and the outer casing of a pneumatic tire to protect the inner tube.

An object of this invention is to provide a novel type of prong which is preferably in the form of a staple of substantially uniform cross section throughout the length of the stock of which the staple is formed, the pointed portions projecting through the outer plies of the boot and the resulting open bight portions being embedded between the cemented plies. Thus each prong will consist of a pair of pointed ends and I am thus enabled to not only increase the number of prongs but also reduce the cross section of the prongs, thereby gaining in strength and at the same time reducing the size of the holes in the casing resulting from insertion of the prongs therein.

A further object is to bend the staples between their pointed ends and their bights so that the open bent bights can lie between the plies of material of which the boot is formed, the plies of the boot being cemented together both inside and about the open bight portions.

My invention has many other features and objects which will be more fully described in connection with the accompanying drawing, and which will be more particularly pointed out in and by the appended claims.

40 In the drawing:—

Figure 1, is a longitudinal sectional view of a boot embodying the features of my invention.

Fig. 2, is a plan view thereof.

Fig. 3, is an enlarged cross sectional view.

Fig. 4, is a face view of one of the staples before it is bent.

Fig. 5, is an edge view thereof.

Fig. 6, is a side view of the staple after 50 being bent.

Fig. 7, is a plan view thereof.

Fig. 8, is an edge view of the staple after the same has been bent.

Like characters of reference designate 55 similar parts throughout the different figures of the drawing.

As shown, 1 designates a boot, as a whole, which is shown as being formed of five plies of sheet material, suitably cemented together and numbered 2, 3, 4, 5 and 6, although I do not wish to be limited to this specific number. It will be seen that on the ends, the plies are successively reduced in length to taper off the ends from the maximum thickness of the boot to a minimum edge or margin thickness. The same is true at the side edges, the purpose being to protect the inner tube from being pinched in abutment abreast of a sharp abrupt edge of the boot and the casing. Thus, I will use letters *a* and *b* to designate the length of the major or maximum thickness of the boot, lengthwise thereof, and the letters *c* and *d* to indicate the width of the major thickness, between which limits it is a feature of my invention to confine the prongs.

Substantially equally spaced throughout the area of the thick portion of the boot, for insertion into the casing, is a plurality of prongs indicated as a whole at 7. These prongs, in the preferred form, are staples, and I will first refer to the specific form of staple used before further describing my improved boot, as my improved staple itself, as an article of manufacture, presents novel features.

The pointed end portions 8, are of sufficient cross section to exercise, collectively, a more than adequate holding action, owing to the number of staples used. The points 90 are sharpened, as at 9, so that they will readily enter the casing and yet form relatively reduced sized openings therein, comparatively speaking. The bight portion of the staple, indicated at 10, is flattened, so 95 that its edges will be knife edged, the purpose of which will presently appear. On line marked 11, the bight portion of the staple is bent at substantially right angles to the pointed portions thereby disposing 100 all of the flattened portion in a position to lie between the plies of the boot. By means of the knife edges with which the bight portions are provided, the cemented plies between which the bight is disposed, are not 105 separated by abrupt edges and this fact greatly reduces the extent of air bodies which would otherwise be present between the plies after they are vulcanized. It is well known that separation of vulcanized 110 plies, in a structure of this nature, invites friction and rubbing such as will in time

absolutely "chew" the fabric to pieces. In accordance with my invention, it is possible to so nearly eliminate the presence of air bubbles as to render them nugatory.

- 5 As shown in Fig. 1, the open bight bases 10, lie flat upon the ply 3, and the pointed portions 8, project through plies 4, 5 and 6. Thus, there are a greater number of plies above than below the bight bases. The purpose of this arrangement is to stiffen the pointed ends as much as possible by reason of their engagement with the three plies. Further, it is a feature of my invention to dispose the bights 10, facing the crown portion 12 by reason of the fact that when a tire is blown up, the "draw" is toward the crown, as regards the boot. This arrangement serves to strengthen the staples.

It is objectionable to separate the vulcanized plies of the boot with metal, as the separated portions tend to work loose, and when this working loose defect starts, it generally continues until a considerable portion or area of adjacent plies are free from each other and begin to "work" and cause destructive friction. Especially is this true where metal of any extensive area is interposed between the plies.

Now while I propose to insert metal between the plies of the boot, and because of this fact, cannot wholly eliminate the objection, still, because my staples are formed of stock of substantially uniform cross section throughout its length, the defect is reduced to a minimum. It will be seen that in the space marked 13, the opposing plies may take the cement so that they will only be actually separated by just that area of the flattened bight and the juncture of the opposing plies will be united all around the bight. At this point, it will now be clear that the uniform disposition of the prongs throughout the area of the boot will assist in holding the boot in firm connection with the casing thereby preventing any surface portion from rubbing and thereby heating and working loose. Thus the character of the prongs, together with their disposition, combine to avoid one of the greatest objections to boots now on the market.

It is believed that the advantages and utility of my invention will be fully understood from the foregoing description, and while I have herein shown and described one form of my invention, I do not wish to be limited thereto except for such limitations as the claims may import.

I claim:—

1. A repair boot for insertion between the inner tube and the casing of a pneumatic tire, comprising in combination, a boot body, and a plurality of staples formed of stock of substantially uniform cross section throughout its length and having their pointed ends projecting from said body for insertion into the casing, the open bights of said staples being embedded in said body.

2. A boot for insertion between the inner tube and the casing of a pneumatic tire, comprising in combination, a boot body formed of a plurality of plies of material suitably cemented together, and a plurality of staples formed of stock of substantially uniform cross section throughout its length and having their pointed ends projecting through the outermost ply for insertion into the casing, the open bight portions of said staples being bent at such an angle to the pointed end portions as to lie flat between said plies and be held in place by the cemented plies inside and about the limbs of the bent bight portions.

3. A repair boot for insertion between the inner tube and the casing of a pneumatic tire, comprising in combination, a boot body formed of a plurality of plies of material suitably cemented together, and a plurality of staples having their pointed ends projecting through the outermost plies for insertion into the casing, the open bight portions of said staples being bent to lie between the plies of the boot and the edges of said bight portions being chamfered to reduce the formation of air pockets, the adjacent plies being cemented together between and about the open bent bight portions.

In testimony that I claim the foregoing as my own, I hereby affix my signature.

RICHARD C. BIGHAM.
